UNITED STATES PATENT OFFICE.

ERAZM. J. JERZMANOWSKI, OF NEW YORK, N. Y.

PROCESS OF GENERATING GAS.

SPECIFICATION forming part of Letters Patent No. 278,145, dated May 22, 1883.

Application filed November 4, 1882. (No model.)

To all whom it may concern:

Be it known that I, ERAZM. J. JERZMANOWSKI, of the city, county, and State of New York, have invented a new and useful Improvement 5 in Processes of Generating Gas, of which the following is a full, true, and exact description, reference being had to the accompanying drawing.

This invention relates to an improvement in 10 the method of producing hydrogen gas, patented to C. M. Tessié Du Motay. In said process a lime-chamber is used, in which steam and naphtha vapor are converted in the presence of hot lime, the lime in said chamber being heated by combustible gases produced in independent retorts from coal. By my improvement I am enabled to dispense with said 15 independent gas-generator for heating the lime in the generator, and am enabled to utilize the same pipes and connections for heating the generator, and for supplying the material to be converted into gas.

The invention will be clearly understood from 20 the accompanying drawing, in which A represents the generator, filled with lime, as described in said Tessié Du Motay patent. B represents the pipe through which the hydrogen gas produced is to be delivered; C, an escape pipe or chimney. D, E, and F represent 25 pipes for supplying steam, air, and naphtha, respectively.

Assuming the lime to be heated, the valves 30 in pipes D and F will be open, thereby injecting steam and any liquid hydrocarbon—such as petroleum, naphtha, &c.—upon the hot lime, whereby the same are decomposed, resulting 35 in the production of hydrogen gas, which will pass through pipe B, to be treated in subsequent operations. After the lime has been

cooled below the point at which conversion 40 occurs, the valve in pipe B is closed, and a valve in chimney C opened. Then, air being admitted through pipe E, a combustion will occur of the steam, air, and naphtha, or other hydrocarbon liquid, making an intense heat, 45 and again raising the lime to the point of conversion. Of course if the lime were not sufficiently hot to light the injected steam, air, and hydrocarbon, a suitable apparatus should be provided for initiating their combustion, 50 which would be the case when the lime was cold. By this process I greatly simplify the previous method and avoid the use of coal in the process, and I also get rid of the additional gas-generator. The effect also upon the 55 lime of this combustion is much superior to the effect produced by water-gas, because no sulphuric impurities are driven upon it, and therefore the gas resulting from the subsequent injection of steam and naphtha is purer. 60

It is obvious that some other arrangement 65 besides that of the pipes D, E, and F might be employed, and also that steam need not necessarily be injected in heating the lime, although I prefer to do so.

What I claim as my invention, and desire to 70 secure by Letters Patent, is—

The process of producing hydrogen gas, which consists in subjecting steam and liquid hydrocarbons to contact with a heated body 75 of lime until said lime has become cool, and in then heating said lime by the combustion of steam, liquid hydrocarbon, and air, substantially as described.

ERAZM. J. JERZMANOWSKI.
